(57) CLAIM

The ornamental design for a football tee, as shown and described.

DESCRIPTION

FIG. 1 is a perspective view of a football tee;
FIG. 2 is a front elevation view of the football tee;
FIG. 3 is a rear elevation view of the football tee;
FIG. 4 is a left elevation view of the football tee;
FIG. 5 is a right elevation view of the football tee;
FIG. 6 is a top elevation view of the football tee;
FIG. 7 is a bottom elevation view of the football tee; and,
FIG. 8 is a perspective view of the football tee, shown in use supporting a football.

The football is shown in broken lines for illustrative purposes only and forms no part of the claimed design.
